RIB APPLYING MACHINE

Joseph C. Antell, Lynn, Mass., assignor to Prime Manufacturing Company, Lynn, Mass., a corporation of Massachusetts

Application February 11, 1957, Serial No. 639,533

14 Claims. (Cl. 12—20)

This invention relates to the preparation of welt insoles by adhesively attaching the required sewing rib to otherwise flat insole blanks. The invention comprises a new and improved process of heat sealing the rib stripping to the insole and novel mechanism for carrying out the process.

The shoemaking industry constantly demands an adhesive bond or union of rib and insole of greater and greater strength and permanence in use as well as a bonding that will unite the rib stripping quickly and securely to insole blanks of synthetic composition which replace leather insoles in certain types of footwear.

The present invention fills this longstanding want by providing a practical shoemaking process characterized by the employment of heat-activatable cement in securing the rib to the insole. It has been found that the process may be carried out successfully by delivering heated air to one or both of the opposed faces of an insole and rib stripping as these elements, coated with a heat-activatable cement, are brought progressively into engagement. The cement upon the opposed faces of these two elements is thus activated and a permanent heat seal bond created by pressing them together preferably as a part of the work-feeding operation.

The machine for carrying out the above process is characterized by rotary means for supporting from beneath an insole blank coated with heat-activatable cement on its upper face and means for guiding rib stripping having a downwardly directed similarly coated face, and directing it progressively into contact with the insole, in combination with means for directing hot air to either or both of the coated faces of the insole and stripping or to the operating instrumentalities of the machine.

As herein shown the guide foot for the rib stripping is utilized for the double function of properly guiding the stripping into contact with the sole blank and also of heating the coated faces of the stripping and sole blank by directing hot air against them.

The machine herein shown includes in its organization an air compressor and a heating unit through which air is forced on its way through the work. In this connection an important feature of the machine resides in means for interrupting delivery of hot air to the work or to the guide foot when the stripping is not traveling through the guide foot or when the sole support is moved to inoperative position. By such means all danger is obviated of overheating the operative instrumentalities of the machine and of scorching the operator's hands.

These and other features of the invention will be best understood and appreciated from the following description of a preferred embodiment thereof selected for purposes of illustration and shown in the accompanying drawings in which:

Fig. 1 is a diagrammatic view showing the elements of the selected embodiment in elevation, partly in section,

Fig. 2 is a view of the guide foot and associated parts, the guide foot being shown in elevation and partly in section,

Fig. 3 is an end view of the guide foot.

2

Figs. 4 and 5 are views in plan and elevation of the bottom plate of the guide foot,

Fig. 6 is a corresponding end view, and

Fig. 7 is a bottom plan view thereof.

In Fig. 1 is shown a portion 10 of the frame of the machine upon which all the elements are mounted. Pivottally attached to the frame is a forwardly extending arm 11 terminating in a hand lever and in this arm is journaled a sole-supporting roll 12 freely rotatable about a horizontal axis. A vertical rod 13 is connected to the arm 11 and has a compression spring 14 encircling its upper portion. The spring bears at its lower end on a boss 15 projecting from the frame 10 and at its upper end against a collar 16 adjustable upon the rod. The spring, therefore, tends at all times to lift the arm 11 and to subject to yielding pressure the sole and rib stripping supported thereon. A toggle 16 is also connected to the arm 11 and serves to hold the arm and the roll 12 temporarily in a lower inoperative position when the arm is depressed by the operator at the conclusion of one operation and preparatory to the insertion of fresh work.

Cooperating feed feet 17 and guiding mechanism for rib stripping are supported by the frame at a fixed level by means not herein shown but which may correspond to similar parts illustrated in U. S. Patent No. 2,142,332, Ridderstrom. The feed feet 17 are operated to engage the rib stripping immediately upon its application to an underlying sole blank, to press the flanges of the applied rib and sole together, and to feed the sole toward the left as shown in Fig. 1.

The guiding mechanism for the rib stripping includes a segmental carrier plate 18 located at a fixed level by connections not shown with the frame and supported for adjustment about the point 20 at which the rib stripping emerges to make its first contact with the underlying sole blank. The lower portion of the plate 18 is undercut to provide a lower face 19 which constitutes the top of the passage for the rib stripping and this face extends substantially to the point 20 of emergence of the stripping. A back plate 21 is secured to the segmental plate 18 in position to form the rear wall of the passage as best shown in Fig. 3.

To the front of the segmental plate 18 is secured an angle plate 22 having a horizontal foot portion 23 provided with perforations 24. The foot portion 23 on this plate forms the bottom of the rib stripping passage as well as the top of a hot air chamber which is an important part of the guide foot as a whole. Hot air is supplied to this chamber through a nipple 25 which extends upwardly from the portion 23 of the angle plate.

A bottom plate or casing 26 is secured by screws to the portion 23 of the angle plate. This is shaped to enclose an elongated hot air chamber which tapers forwardly and is provided with perforations 27 opening through its bottom face where it makes direct contact with the cement-coated insole blank 40 as well shown in Fig. 2. The guide foot as a whole directs the rib stripping 41 to the insole at an inclination of about 30°, and the lower wall of the bottom plate 26 has an inclined portion at substantially the same angle so that its perforated portion shall bear over considerable area upon the sole blank. The portion 23 of the angle plate and the lower wall of the bottom plate 26 are tapered to present a sharp edge 28 immediately below the point 20 of the segmental plate 18 and just beyond the area of the insole heated through the medium of the bottom plate 26.

A cylindrical heating unit 30 is permanently mounted upon a convenient portion of the frame and provided with a U-shaped element 31 in circuit with a source of electric power by which it is maintained at high temperature. The frame also carries an air compressor 32

operated by a motor 33 and arranged to deliver air to the heating unit 30 wherein it is raised to a high temperature. The unit 30 discharges through a pipe 34 to a valve 35 secured to the top of the frame 10. The valve is operated by an arm 37 which is connected through a sleeve 38 to the top of the rod 13. The valve 35 has an outlet to the atmosphere shown as upwardly directed, and an outlet to a pipe 36 which is connected to the nipple 35 of the guide foot.

When the arm 11 occupies its upper and operative position the valve 35 directs heated air through the pipe 36 to the hot air chamber of the guide foot from whence it is delivered continuously upwardly to the rib stripping and downwardly to the coated insole blank 40. However, when the sole support 12 and the arm 11 are moved downwardly to inoperative position and held temporarily in that position by straightening the toggle 16, the valve is operated through the rod 13 to cut off heated air from the pipe 36 and the guide foot and to discharge it temporarily to the atmosphere.

The operation of the machine will be clear from the foregoing description. It will be understood that the insole blank 40 has been provided, before it reaches the machine, with a marginal coating of heat-activatable cement, the coating being indicated in Fig. 2. The flange portions of the rib stripping have also been similarly coated. These two coated surfaces are activated by heated air and by their contact with the heated surfaces of the portion 23 and the bottom plate 26 as they progress beneath and through the guide foot. As the stripping emerges at the point 20 it is immediately engaged by one or other of the feed feet 17. These are forked or grooved to straddle the rib and step on the inner and outer flanges of the strip, pressing them down upon the insole and effecting the desired heat-sealed union of the parts.

The process of my invention is not herein claimed but forms the subject-matter of my co-pending application Serial No. 720,711, filed March 11, 1958.

Having thus disclosed my invention and described in detail a preferred embodiment thereof, I claim as new and desire to secure by Letters Patent:

1. A rib applying machine having a sole-supporting member, a strip-guide mounted above it and having a passage for directing rib stripping to the surface of an insole on the supporting member, means for leading heated air to the passage of the strip-guide to heat stripping passing therein, and means for directing heated air to the surface of the insole as it approaches contact with the stripping.

2. In a rib applying machine a strip-guide having a hollow bottom plate and enclosing a passage above the plate for rib stripping, hot air connections to the bottom plate and perforations in its lower face whereby hot air is directed to the surface of an underlying insole.

3. A strip guide as defined in claim 2 in which the bottom plate is tapered to a thin edge for engaging the insole.

4. A strip guide as defined in claim 4 in which the bottom plate has perforations opening upwardly into the passage for the rib stripping.

5. A strip guide as defined in claim 2 in which the hollow bottom plate has perforations for the escape of hot air through both its upper and lower faces.

6. A rib applying machine having, in combination, a forwardly tapering strip-guide and sole support movable with respect to each other from an inoperative to an operative position in which rib-stripping is presented at an acute angle by the strip-guide to a sole on the support, hot air connections to the strip-guide including a normally closed valve and valve-operating means acting to hold open said valve only while said strip-guide and sole support occupy their operative position.

7. A rib applying machine having a frame, a strip-guide mounted thereon at a fixed level, a sole support

mounted beneath the guide, means for movably maintaining the sole support in elevated operative position with respect to the strip-guide, and hot air connections to said guide including a valve connected to the sole support.

8. A rib applying machine having a strip-guide mounted at a fixed level and having an elongated closed passage for heating rib stripping as it passes therethrough, air connections to the guide including a heating unit and valve, a sole support beneath said guide, and means for simultaneously lowering the support to inoperative position and closing the valve to cut off hot air from the guide.

9. A rib applying machine comprising a strip-guide mounted at a fixed level, a hinged arm carrying a sole-supporting roll and holding it in operative relation with respect to the strip guide and beneath the same, the strip-guide having a hollow bottom plate tapering inwardly toward the roll, hot air connections entering the plate, and exit perforations in its lower surface arranged to discharge hot air upon a sole supported by said roll.

10. In a rib applying machine, a sole support and a cooperating strip-guide, the strip-guide having a longitudinal passage for directing rib stripping to a sole on said support and containing a hot air chamber having exit apertures directed toward the sole and also toward said passage.

11. In a rib applying machine, means for movably supporting from beneath an insole blank coated with a heat-activatable cement on its upper face, a tapering guide foot with an inclined passage for guiding rib stripping having a downwardly directed similarly coated face and directing it progressively at an acute angle into contact with the coated face of the insole and simultaneously directing hot air to the convergent coated faces of the insole and stripping, and means for causing the heated surfaces to make permanent engagement with each other.

12. In a rib applying machine, a toggle supported roll and work feeding feet cooperating to advance an insole to which a rib has been adhesively attached, a guide foot for directing cement coated rib stripping to an insole blank resting on said roll, an air system for delivering heated air to the guide foot and including an electric heating unit and a valve located between said unit and the guide foot, and connections between the toggle and valve for discharging air from the system to the atmosphere when the toggle is straightened.

13. In a rib applying machine, a rotary sole support and a guide foot for directing rib stripping to a sole on said support, the guide foot having walls forming a hot air chamber with an elongated passage for the stripping above the chamber and a sole-engaging plate below the chamber, the passage and plate converging to direct the emerging stripping into contact with the sole beyond an area of the insole which is heated by said sole-engaging plate.

14. In a rib applying machine, a rotary sole support and a guide foot for heating rib stripping and directing it to a sole on said support, the guide foot having walls forming a hot air chamber tapering toward the point of initial contact of the rib stripping with the sole, an elongated passage for the stripping above said chamber and a sole-engaging surface inclined toward the exit end of said passage, and hot air connections to said chamber adjacent its larger end.
